UNITED STATES PATENT OFFICE.

CHRISTA E. WILLSON, OF ZIONSVILLE, INDIANA.

DESIGN FOR A PINCUSHION.

Application filed October 3, 1921. Serial No. 505,187. Term of patent 7 years.

To all whom it may concern:

Be it known that I, CHRISTA E. WILLSON, a citizen of the United States, residing at Zionsville, in the county of Boone and State of Indiana, have invented a new, original, and ornamental Design for a Pincushion, of which the following is a specification, reference being had to the accompanying drawing, forming part thereof.

I claim:

The ornamental design for a pincushion as shown.

CHRISTA E. WILLSON.
